UNITED STATES PATENT OFFICE.

GEORGE HENRY SCHMUNK, OF CRANBERRY TOWNSHIP, BUTLER COUNTY, PENNSYLVANIA, ASSIGNOR TO PITTSBURGH STOGIE AND CIGAR COMPANY, OF PITTSBURGH, PENNSYLVANIA, A CORPORATION OF PENNSYLVANIA.

PROCESS FOR PACKING STOGIES.

1,097,142.

Specification of Letters Patent.

Patented May 19, 1914.

Application filed October 10, 1912. Serial No. 724,916.

To all whom it may concern:

Be it known that I, GEORGE HENRY SCHMUNK, citizen of the United States, and residing in the township of Cranberry, in the 5 county of Butler and State of Pennsylvania, have invented or discovered new and useful Improvements in Processes for Packing Stogies, of which the following is a specification.

10 My invention consists of a new and improved process for packing stogies in drums or other containers wherein the stogies are placed vertically or on end.

15 Stogies which have not been subjected to considerable and prolonged pressure are lacking in the desirable smoking qualities. They burn unevenly, unwrap and fray, and are markedly lacking in flavor. It is therefore the custom to pack the stogies as tightly 20 and snugly as possible in the container to compress them and obtain the improved quality. In the case of stogies which are packed in drums or other containers wherein the stogies are placed vertically or on end

25 and from which the stogies are removed by seizing them by their ends and pulling them out lengthwise, the removal of the first few of the stogies, if the same be tightly packed, would result in tearing off the ends of the 30 stogies and rupturing the wrapper. The customer, of course, throws these aside and they are a dead loss to the retailer. The result is that stogies are commonly packed loosely in such containers and therefore do 35 not receive the beneficial results of tight packing and compression. The use of these containers is now generally confined to the poorer grades of stogies.

40 My object is to pack the stogies in such a container with the required degree of snugness and compression and at the same time provide means whereby the stogies may be individually removed lengthwise from the container without the slightest danger of 45 pulling off or tearing their ends or rupturing their wrappers.

45 My process is as follows: The stogies when freshly made together with a foreign object, such for instance, as a card board tube having a smooth surface, are rolled or gathered in a strip of paper or other support into a compact bundle or bunch of proper density and compression to preserve and improve the smoking qualities of the stogies and of

proper size to slip snugly into the container 55 longitudinally. The bunch is then slipped endwise into the container. The stogies are thus properly packed and compressed. When placed on sale, the cover of the container is removed and the tube or other foreign object 60 pulled longitudinally from the bunch of stogies, the former slipping out easily, as its sides are smooth, without injury to the stogies. The stogies are thus left loose enough in the container to permit their 65 ready removal without the breaking or pulling off of their ends or rupturing or tearing of their wrappers as is the case where no foreign object is packed with them and first removed from the container before attempting 70 to remove the stogies. The tube or other foreign object is preferably of sufficient length to substantially span the distance between the bottom of the container and the cover, when the latter is in place, thus supporting the cover against crushing down 75 upon the stogies as frequently happens in the ordinary container.

In the accompanying drawings, Figure 1 is an end elevation showing a quantity of 80 stogies and a foreign object gathered on a piece of paper preparatory to being rolled and compressed together into a bunch to fit the container; Fig. 2 is an elevation of the bunch; Fig. 3 is a vertical section of a drum 85 showing the bunch packed therein, and Fig. 4 is a similar view showing the lid and the foreign object removed and the stogies loosened in the container for dispensing at 90 retail.

The following is a detailed description of my process as the same is illustrated in the drawings.

A represents a strip of paper, cloth or other convenient material upon which is 95 placed the quantity of freshly made stogies 1—1, as for instance one hundred, which are to be packed in the container.

B is a foreign object as a smooth card board tube, preferably of slightly greater 100 length than stogies 1—1, which is placed with the latter on the paper A. The packer then seizes the ends of the paper A and rolls and manipulates its contents until the latter assumes the form of a tightly compressed bunch, as shown in Fig. 2, the paper A surrounding the same with its ends overlapping.

C is the drum or other container, usually of card-board and of slightly less height than the stogies 1—1, so that when on sale the ends of the stogies are exposed to view 5 and may be conveniently seized for withdrawal.

D is a lid of any convenient type, shown for the sake of illustration as of the type now in general use wherein a depending 10 flange 2 slips down over the top of the drum C. The bunch, shown in Fig. 2 is now pushed down into the drum C and the lid D put on, the upper end of the object B supporting the lid out of contact with 15 the ends of the stogies 1—1 and thus protecting them from breakage.

When the stogies are to be exposed for sale, required by law to be in the original package, the lid D is removed and the object C withdrawn vertically. This withdrawal is readily accomplished as the sides of said object are smooth and do not rupture or tear the stogies and the protrusion of the 20 end of said object above the stogies provides 25 a convenient finger grasp. With the withdrawal of the object B, the stogies are loosely contained in the drum, as shown in Fig. 4, and may be easily and safely withdrawn by the purchasers.

As a result of my improved process the field of the "drum" package has been greatly extended. Owing to the impossibility of withdrawing a tightly packed stogie from a drum without destroying the 30 former, this form of package has been used exclusively for low grade, loosely packed goods, but by the use of my new process of packing, the drum, the cheapest and in 35 many ways the most desirable form of package, is adapted for use in connection with 40

stogies of the very finest quality and most expensive grades, and the poorer grades are much improved in quality by being packed by my process.

What I desire to claim is:—

1. The process of packing stogies tightly 45 in a container which consists of gathering a quantity of uncompressed stogies about a smooth-walled foreign object and manipulating the same into a tightly compressed 50 bunch and then inserting said bunch endwise into a snugly fitting container, said foreign object when in place in said bunch holding said stogies in the required compression but being adapted to be drawn out 55 longitudinally so that the stogies will remain loosely in said container for easy removal.

2. The process of packing stogies tightly 60 in a container which consists of gathering a quantity of uncompressed stogies about a smooth walled foreign object and manipulating the same into a tightly compressed bunch and then inserting said bunch endwise into a snugly fitting container, said 65 foreign object when in place in said bunch holding said stogies in the required compression but being adapted to be drawn out longitudinally so that the stogies will remain loosely in said container for easy removal, and said foreign object being of sufficiently greater length than the stogies to support the lid of the container out of contact with the stogies.

Signed at Pittsburgh, Pa., this 8th day of 75 October, 1912.

GEORGE HENRY SCHMUNK.
